WINDOW ELEMENT AND LOCKING MEANS

Robert W. Banks, Memphis, Tenn.

Original application June 30, 1936, Serial No. 88,230. Divided and this application May 10, 1937, Serial No. 141,825

2 Claims. (Cl. 292—101)

This invention relates to window elements and more particularly to a locking means therefor, as originally disclosed in my application filed June 30, 1936, Serial Number 88,230, of which 5 this application is a divisional application.

One of the important objects of this invention is the production of a simple and efficient means for locking the upper and lower window sashes and remotely anchoring the locking means in a 10 manner whereby the anchoring means will be shielded from view from the outside of the window.

A further object of this invention is the production of a simple and efficient lock which is 15 so constructed as to firmly draw the upper and lower sashes together in a locked position as the hook is swung to a locking position.

Other objects and advantages of this invention will appear throughout the following specification and claims.

In the drawing:

Figure 1 is a front elevation of a window showing my improved locking device applied thereto;

Figure 2 is a horizontal sectional view taken on 25 line 2—2 of Figure 1;

Figure 3 is an enlarged horizontal sectional view taken on line 3—3 of Figure 2;

Figure 4 is a vertical sectional view taken on 30 line 4—4 of Figure 1;

Figure 5 is a perspective view of the hook engaging link;

Figure 6 is a perspective view of the locking hook.

By referring to the drawing, it will be seen that 35 A designates the window frame which may be of the type of structure such as is shown. In carrying out my invention, I preferably slidably mount an upper sash frame 10 within the window frame or casing A, and also slidably mount 40 a lower sash frame 11 within the window frame or casing A. These sash frames 10 and 11 may be connected to the counter-weights 12 through the medium of suitable sash cords. The upper sash 10 is provided with a suitable screen 10a and 45 a burglar guard 10b. The lower sash 11 is also provided with a screen 11a and a burglar guard 11b, similar to my previous application Serial Number 88,230.

The bottom sash frame 11 is provided along or 50 adjacent its top edge with a transversely extending elongated aperture 13, in which is pivotally mounted a locking hook 14, as at 15, the locking hook 14 having an offset arm 16 which terminates in a hook end 17. The inner face 18 of 55 the offset arm 16 is inclined with respect to the

longitudinal axis of the shank 19, the outer end which terminates in the hook 17 being in substantial alignment with the pivot 15, and the shank 19. A pin 20 is extended vertically through a socket 21 formed in the face of the sash 10 which abuts the sash 11, and is adapted to be engaged by the hook and the offset arm 16. It will therefore be seen that as the hook 14 is swung in the direction of the arrow shown in Figure 3, the inclined face 18 of the offset arm 16 by engaging the pin 20, will cause the sashes 10 and 11 to be drawn tightly together. The harder the pull in the direction of the arrow shown in Figure 3, the tighter the clamping action of the hook 17 and arm 16 upon the pin 20.

The shank 19 normally extends outwardly beyond the sash 11 projecting from the elongated aperture 13 and the outer end of the shank 19 carries a vertically extending pin 22, which pin extends above and below the shank 19, as shown 20 in Figures 4 and 6.

An elongated link 23 engages the shank 19 and is provided with an elongated slot 24 through which the shank 19 extends, the slot 24 terminating at one end in a right-angularly extending slot 25 for permitting the vertically extending pin 22 to pass therethrough in a vertical position and to allow the shank 19 to slide longitudinally through the slot 24, thus providing an efficient detachable connection between the link 23 and the shank 19. 30 The link 23 is engaged near the transverse or vertical slot 25 by means of an anchoring chain 26. This chain 26 carries a snap hook 27 at its outer end for engaging the eye 28 of an anchoring plate 29. The anchoring plate 29 is preferably positioned to the wall, at one side of the window frame or casing A, as shown in Figure 1, in transverse alignment with the overlapping portions of the upper and lower sashes 10 and 11 and in substantial alignment with the link 23 and 40 hook 14 so as to extend the chain 26 across the inner face of the window and in close proximity to the overlapping portions of the sash. In this way the anchoring chain 26 will be anchored at a considerable distance from the window sash 45 beyond reach of an unauthorized party reaching through the window from the outside.

It should be further understood that the hook 14 may not be swung to an open position until the snap hook 27 is released with the chain 26, 50 since the plate 29 and eye 28 are located at a selected position to hold the chain 26 taut when the hook 14 engages the pin 20 in a locking position, such as is shown in Figures 1, 2 and 3. Furthermore, it will be seen that when it is desired, 55

the link 23 may be detached from the hook 14 by merely sliding the link along the shank 19 to a position whereby the pin 22 registers with the slot 25, permitting the pin 22 to slide through the slot 25 for disconnecting the hook 14 from the link when desired.

It should be understood that certain detail changes in the mechanical construction may be employed without departing from the spirit of the invention, so long as such changes fall within the scope of the appended claims.

Having described the invention, what I claim as new is:

1. A fastener for window sashes and the like comprising a locking hook having a pivot support adapted to be carried by one sash and means carried by the hook for engaging means on an adjoining sash for locking two adjoining sashes together, said locking hook having an elongated shank adapted to project beyond one sash, the outer end of the shank having right angularly extending stop means, an elongated detachable link

having a T-shaped slot for receiving the outer end of the shank, the right angularly extending stop means of the shank being adapted to enter the slot at one end and adapted to overhang the sides of the slot as the shank is moved longitudinally of the slot for detachably holding the link in engagement with the shank, and flexible anchoring means carried by the link and adapted to be secured remotely at one end for holding said locking hook in a set position.

2. A fastener for window sashes and the like, comprising a locking hook adapted to be pivoted upon one sash and having means for locking engagement with an adjoining sash, said locking hook having an elongated shank adapted to project beyond the sash on which the hook is adapted to be mounted, a detachable link fitting over said shank, and a remotely anchored flexible means secured to said link for holding said link and a locking hook against swinging movement in one direction.

ROBERT W. BANKS.
